UNITED STATES PATENT OFFICE

1,992,194

CLOTH FINISHING

Sanford L. Cluett, Troy, N. Y., assignor to Cluett,
Peabody & Co., Inc., Troy, N. Y., a corporation
of New York

Application October 12, 1932, Serial No. 637,438

14 Claims. (Cl. 26—38)

This invention relates to fabric finishing and has for one of its objects the improvement of mechanism adapted to shrink fabric by confining the fabric to the contracting surface of a blanket, 5 as described in my United States Patent No. 1,861,422 and No. 1,861,424, granted May 31, 1932. The former of these two patents describes the general method of shrinking fabric by such mechanical means, while the latter patent describes 10 and illustrates a machine utilizing the principal parts of a widely used type of ironing and finishing machine but altered and rearranged to provide commercially advantageous mechanism for practicing the process. The present invention aims to simplify mechanism for shrinking fabric mechanically in such a way as to leave in the shrunken fabric a commercial finish as distinguished from inferior finishes obtained by washing and the like, and further aims to provide 15 shrinking mechanism which can be constructed from commonly used ironing, drying and finishing machines with the minimum of alteration.

One feature of the device of my Patent No. 25 1,861,424 comprises pressure means, preferably in the form of a series of metal blocks, adapted to confine the entering fabric to the relatively extended surface of the traveling blanket on the intake roll before the fabric contacts with the 30 drying cylinder of the machine, for the purpose of causing the fabric to partake of the surface contraction of the traveling blanket. One object of the present invention is to provide an improved construction including an intake roll or analogous blanket guiding means, and pressure means better adapted to operate in conjunction with the drying cylinder to enable the machine to produce shrinkage. In particular the invention aims to avoid necessity for accurate 35 alignment of the intake roll and surface of the drying cylinder, to avoid necessity for a high degree of regularity of the drying cylinder, and to avoid wear of either the drying cylinder or the pressure means such as has heretofore been possible because of the previous relationship of these parts.

It will be observed from a consideration of my Patent No. 1,861,424 that the mechanism therein described involves the transfer of the fabric from confinement by the pressure means such as heated ironing blocks to similar confinement against the heated drying cylinder. In the device of said patent, it is preferable that the pressure means which first confines the fabric shall 50 extend as nearly as possible to the exact point

where the fabric is subjected to pressure by the drying cylinder; it is sought by such construction to avoid permitting the fabric to leave the contracting surface of the blanket and consequently to wrinkle. The present invention aims to avoid any necessity for the pressure means extending into substantial contact with the drying cylinder, and further aims to provide for a structurally desirable spacing of these parts without any detriment to the cloth under treatment.

Moreover, it is an object of this invention to provide shrinking apparatus improved in its capability of diminishing the length of rayons, silks, voiles or any fabric requiring especial care to prevent its warp threads from being forced 10 out of longitudinal alignment during the process. The device of my Patent Number 1,861,424 accomplishes a result which is commercially satisfactory in this regard by maintaining the previously described close relation between the pressure means and the drying cylinder. However 15 the present invention (without the necessity for such close relation of parts) provides an even improved alignment of the warp threads by subjecting the fabric to a very slight longitudinal 20 stretch immediately after the fabric has contracted in length, and before it is dried. Such slight longitudinal stretch is insufficient to make any practical difference in the ultimate length or shrunken dimension of the fabric, but is sufficient to improve substantially the warp-alignment 25 of certain fabrics such as mentioned above.

Other objects of the invention, and features of novelty and advantage will be apparent from this specification and its drawings wherein my 30 invention is explained by way of example.

In the drawings:

Fig. 1 is a vertical sectional view showing the intake roll and pressure means, and a fragment of the drying cylinder and endless blanket of an 40 improved shrinking device, this view being taken on the line 1—1 of Fig. 2;

Fig. 2 is an end elevation to a smaller scale of the machine of Fig. 1, parts being broken away on the right-hand half of this view to show 45 other parts normally obscured thereby;

Fig. 3 is a vertical sectional view taken on the line 3—3 of Fig. 2; and

Fig. 4 is a diagrammatic view similar to Fig. 1, showing a modification thereof.

The drawings show the machine as having a frame 10, a rotary heated drying cylinder 11, an endless blanket 12 of any appropriate material that may be readily flexed so that the surface stretches or contracts during flexure, traveling 55

in a path defined in part by the cylinder, and an intake roll 13. All of these parts may be and preferably are the same as those employed in a common type of fabric-finishing and ironing machine. In particular the intake roll 13 is preferably spaced substantially away from the drying cylinder 11, being mounted at its ends in bearings 14, 14 which are preferably carried by adjustable frames 15, 15. These adjustable frames 15, 15 and bearings 14, 14, may be like those customarily employed to adjust and mount an intake roll in approximate parallelism with the heated cylinder of a drying machine, and in particular need not have any such adjustability as would permit the intake roll to nip the blanket against the cylinder 11. On the contrary, it is preferred that the intake roll should be several inches away from the drying cylinder as in drying machines which are not concerned with shrinking. Thus Figure 1 shows a distinct gap across which the blanket 12 runs from intake roll 13 to drying cylinder 11.

To such old and well-known parts, there is preferably added a supplemental pressure roll 18 adapted to force the blanket against the drying cylinder at a point below the intake roll, thus predetermining the point at which the blanket runs onto the cylinder. This supplemental roll, which is in certain aspects of the invention an optional feature (omitted in the modification, Fig. 4) may conveniently have its end bearings 19 suspended by links 20 hanging from the shaft 22 of the offtake roll, and may advantageously be forced toward the cylinder by springs 25 cooperating with links 26 which are fastened to the frame 10.

Fabric W, coming from any preceding treatment such for example as moistening, or calendering or other finishing operations approaches the apparatus as shown in Fig. 1 so as to contact first with the convex and relatively extended surface of the blanket 12 passing over the intake roll 13. The fabric is then pressed and held into confinement against this surface of the blanket to cause it to partake of contraction of the surface of the blanket as the latter leaves the intake roll. Pressure means for thus confining the fabric preferably take the form of a plurality of steel ironing blocks 29 heated by internal electric heating elements 30 to prevent sticking, and having polished concave surfaces accurately conforming to the convexity of the blanket 12 on the intake roll. The pressure means moreover acts to press the fabric against the blanket after the latter leaves the convex surface defined by the intake roll, and accordingly, the blocks 29 are shown as having depending portions 29^a extending down into the gap between the intake roll and cylinder. Preferably, as shown in Fig. 1, the concave surface of the pressure means merges into a slightly convex surface in the portion 29^a so that the blanket surface not only loses its convexity but assumes an opposite concavity in leaving the intake roll. As a result, the fabric, confined to the contracting blanket surface, contracts correspondingly before leaving the lower end of the pressure members 29. The exact amount of such contraction or longitudinal shrinkage depends upon the thickness of the blanket, the size of the intake roll, and the convexity of the lower part 29^a of the pressure means. With the parts constructed as shown in Fig. 1, and with a blanket of 0.40 inch thickness and an intake roll of 3.00 inches diameter, a longitudinal contraction of about 3.7

inches per yard will result, quite sufficient completely to preshrink most kinds of fabrics.

In addition to the advantage of retaining the position of the intake roll 13, spaced substantially from the drying cylinder as in prior ironing devices (thus rendering such prior devices easily adaptable to my method of shrinkage) the herein-described structure is desirable in that it avoids bringing the pressure means, such as the blocks 29, into close relation to the drying cylinder. As shown in Fig. 1, there is preferably a substantial clearance between the lower tip of the blocks 29 and the drying cylinder. This avoids any possibility of the blocks 29 scoring the surface of the cylinder. Further, the clearance permits the lower tip of the blocks 29 to be rounded and avoids the disadvantages of a sharp edge such as is employed in the blocks of my Patent No. 1,861,424. Moreover, with the clearance between the blocks and cylinder, accurate alignment of the intake roll and cylinder is unnecessary.

As shown in Fig. 1, the lower tip of the pressure means may terminate approximately at the point where the blanket runs onto the supplemental roll 18. Between the tip of the pressure means 29 and the cylinder 11, the previously concave surface of the blanket assumes a slight convexity, thus very slightly stretching the fabric which at this point is not subject to normal pressure. This slight stretching is insufficient to make any practical difference in the ultimate length or shrunken dimension of the fabric, but is sufficient to improve the warp-alignment of certain fabrics such as silks, rayons or voiles which have a slight tendency to lose their warp-alignment upon being subjected to mechanical shrinkage.

The fabric thus longitudinally shrunken and then very slightly stretched, then is pressed by the blanket against the rotating drying cylinder, and is thus set in its improved preshrunken condition.

The machine's adjuncts for mounting the pressure blocks 29 may be similar to those described in my Patent No. 1,861,424. This construction may include for example a pair of C-shaped plates 35 suitably affixed to the respective roll-carrying frames 15, a pair of brackets 36 pivotally mounted at 37 on the respective C-shaped plates 35, and a transverse rod 38 connecting the two brackets 36, so as to form a pivoted yoke extending across the width of the series of blocks 29. Each block 29 may carry a hook 39 surrounding the rod 38 so that when the yoke is swung to the right about pivots 37, all the blocks 29 are removed at once from the fabric.

A channel bar 41 may connect the two brackets 36 and serve as a conduit for electric conductors leading to heating units 30 in the several blocks 29.

Each block 29 may have fastened thereto a rearwardly and upwardly extending lip 45 carrying a set-screw 47 adapted to bear against a bracket 48 on the channel 41, thus constituting a fulcrum for the block. A spring 50 engaging the lip 45 and an arm 51 fastened to channel 41, is adapted to urge the block against the web on blanket 12. The lower part 29^a of the block may be forced against the web by the action of a spring 53, which may be adjusted by a set-screw 54 in the lip 45.

The modified form of apparatus of Fig. 4 is in general similar to the apparatus of Figs. 1, 2 and, 3, and corresponding parts are designated by the reference characters of Fig. 1 with the addition

of primes. In the apparatus of Fig. 4, the intake roll 13' and drying cylinder 11' are somewhat closer than are the corresponding parts of Fig. 1, and there is no supplemental pressure roll corresponding to the roll 18 of Fig. 1. Thus in the device illustrated in Fig. 4, there is no provision for slightly stretching the shrunken fabric before drying.

It should be understood that the present disclosure is for the purpose of illustration only and that this invention includes all modifications and equivalents which fall within the scope of the appended claims.

I claim:

- 15 1. A fabric-shrinking machine having therein a heated rotating fabric-drying cylinder, a blanket traveling in an endless path defined in part by said cylinder and adapted to hold a fabric web in contact with the cylinder, guide means for the blanket positioned to cause the fabric-receiving surface of the blanket to contract at a point in advance of and spaced from the drying cylinder, the machine being adapted for the reception of the fabric web by the blanket when the latter is in a relatively extended state preceding said contraction, and pressure means for holding the web against the blanket during contraction thereof.
- 20 2. A fabric-shrinking machine having therein a heated rotating fabric-drying cylinder, a blanket traveling in an endless path defined in part by said cylinder and adapted to hold a fabric web in contact with the cylinder, guide means for the blanket positioned to cause the fabric-receiving surface of the blanket to contract at a point in advance of and spaced from the drying cylinder, the machine being adapted for the reception of the fabric web by the blanket when the latter is in a relatively extended state preceding said contraction, and pressure means for holding the web against the blanket during contraction thereof, said pressure means extending close to the point where the blanket runs onto the cylinder.
- 25 3. A fabric-shrinking machine having therein an intake roll, an endless fabric-receiving blanket passing thereover with its fabric-receiving surface temporarily convex, a heated drying cylinder receiving the blanket from the roll, the roll and cylinder being spaced farther apart than the thickness of the blanket, and a pressure member conforming to the convexity of the blanket on said roll and extending in the space between the roll and the cylinder beyond a point where the fabric-receiving surface of the blanket has lost its convexity in leaving the roll.
- 30 4. A fabric-shrinking machine having therein an intake roll, an endless blanket passing thereover, a heated drying cylinder, there being between the roll and cylinder a gap across which the blanket runs free from both the roll and cylinder, and a pressure member conforming to the convexity of the blanket on said roll and having a portion shaped to press fabric against the blanket during passage of said gap.
- 35 5. A fabric-finishing machine having therein a heated drying cylinder, a blanket travelling in an endless path defined in part by said cylinder, a guide member defining a curved path, of convexity opposite to that of the drying cylinder, there being between said guide member and said drying cylinder a gap in which the surface of the belt contracts before reaching the cylinder, and pressure means for confining fabric to the surface of the blanket on said guide member and to the subsequently contracted surface of the blanket in said gap.
- 40 6. A fabric-finishing machine having therein a heated drying cylinder, a blanket traveling in an endless path defined in part by said cylinder, a guide member defining a curved path of convexity opposite to that of the drying cylinder, there being between said guide member and said drying cylinder a gap in which the surface of the belt contracts before reaching the cylinder, and pressure means for confining fabric to the surface of the blanket on said guide member and to the subsequently contracted surface of the blanket in said gap, said pressure means having a convex surface adapted to cause the fabric-engaging surface of the blanket to assume a concave form in said gap.
- 45 7. A fabric-finishing machine having therein a heated drying cylinder, a blanket traveling in an endless path defined in part by said cylinder, means for guiding the blanket onto the cylinder comprising two rolls, the first substantially spaced from the cylinder and the second adapted to nip the blanket against the cylinder, the surface of the blanket contracting as it leaves the first of said rolls in passing to the second of said rolls, and pressure means for confining fabric to the contracting surface of said blanket, said pressure means acting on the fabric between the two rolls.
- 50 8. Method of cloth-finishing comprising applying a fabric web to a traveling surface of a blanket, holding the fabric against the blanket by pressure, causing the surface of the blanket to contract, thereby contracting the fabric, then stretching the fabric to improve its thread alignment, and fixing the fabric by heat and pressure.
- 55 9. Method of cloth-finishing comprising applying a fabric web to a traveling surface of a blanket, holding the fabric against the blanket by pressure, causing the surface of the blanket to contract in length thereby contracting the fabric, then stretching the fabric to improve its warp alignment, and fixing the fabric by heat and pressure.
- 60 10. Method of cloth-finishing comprising holding a fabric web against a contracting surface by pressure, then releasing the pressure and stretching the fabric, and then fixing the fabric by heat and pressure.
- 65 11. Apparatus for cloth-finishing comprising in combination, means for maintaining a web of fabric under compression, means for forcing the fabric to contract while under such compression, means operable on the thus treated fabric to stretch the fabric, and means for drying the fabric under transverse pressure.
- 70 12. Apparatus for cloth-finishing comprising an endless blanket having a surface adapted to extend and contract, means for causing the said surface to contract, means for compressively holding a fabric web against the blanket during such contraction thereby shrinking the fabric, means for causing the said surface to extend, thereby stretching the fabric, and heated drying means onto which the blanket runs to fix the fabric in its thus attained condition.
- 75 13. Fabric-shrinking apparatus having therein a rotary heated drying cylinder, an endless blanket running in a path defined in part by said cylinder, guide means defining an alteration of curvature of the blanket such that the blanket surface contracts before running onto the cylinder, said guide means being spaced from the cylinder to provide a substantial gap between the cylinder

and the place of said contraction of the blanket surface, and a pressure member extending into said gap for pressing fabric against the contracting blanket surface.

5 14. Fabric-shrinking apparatus having therein a rotary heated drying cylinder, an endless blanket running in a path defined in part by said cylinder, guide means defining an alteration of curvature of the blanket such that the blanket surface contracts before running onto the cylinder.

der, said guide means being spaced from the cylinder to provide a substantial gap between the cylinder and the place of said contraction of the blanket surface, and a pressure member extending into said gap for pressing fabric against the contracting blanket surface, said pressure means having a substantial clearance from the rotating cylinder.

SANFORD L. CLUETT.
